[57] CLAIM

The ornamental design for the tool case for a three-piece
pliers set, as shown and described.

DESCRIPTION

FIG. 1 is a perspective view of a tool case for a three-piece
pliers set in an open position showing my new design;
FIG. 2 is a top view thereof;
FIG. 3 is a front side view thereof, the undisclosed opposite
side being a mirror image;
FIG. 4 is a right side view thereof;
FIG. 5 is a bottom view thereof; and,
FIG. 6 is another perspective view thereof with the case in
a closed position.
